UNITED STATES PATENT OFFICE.

JOHN T. AUSTIN, OF HARTFORD, CONNECTICUT.

AUTOMATIC TRACKER AND SHEET REGULATION.

Application filed February 3, 1925. Serial No. 6,514.

This invention relates to musical instruments of the type having note playing mechanisms, a tracker bar associated with said mechanisms, and a music sheet passing over said tracker bar and having perforations adapted to register with openings in the tracker bar and thereby control the operation of the playing mechanisms.

An aim of the invention is to provide, in 10 a musical instrument of this sort, improved tracker mechanism wherein the tracker bar is automatically elongated or contracted in accordance with variations in width of the music sheet due to atmospheric and other causes.

A further object of the invention is to provide, in combination, an improved tracker mechanism wherein the tracker bar is automatically caused, by the music sheet, to vary 20 in length in accordance with changes in the width of the music sheet, and mechanism, also controlled by the music sheet, for relatively shifting the sheet and tracker bar to cause the sheet to track properly over the 25 tracker bar.

The above and other objects of the invention are obtained in a very simple and effective manner.

In the accompanying drawing, I have 30 shown, more or less diagrammatically, two embodiments which the invention may take, it being understood that these disclosures are by way of exemplification only, and that the structures are susceptible of various 35 modifications and changes. For instance, the operating means for varying the length of the tracker bar and the operating means for shifting the note sheet or tracker bar, one relative to the other, so that the sheet 40 will track properly, are each shown as being in the form of pneumatics or air motors.

In these drawings—

Figure 1 shows, more or less diagrammatically and in elevation, a structure in 45 which the improvements of the present invention are incorporated, and

Fig. 2 is a view similar to Fig. 1, but illustrates another embodiment.

Referring to the drawing, in each of the 50 figures 10 designates generally, a tracker bar formed in sections, in the present instance the middle section 10^a being fixed to a support and the remaining sections being mounted for adjustment towards and away 55 from the middle section. These movable sections may be mounted in a manner gen-

erally similar to that disclosed in my U. S. Letters Patent, No. 1,099,907, granted June 16, 1914, for tracker mechanism for musical instruments. In Fig. 1 the support for the 60 tracker bar is not shown. In Fig. 2 the support is illustrated as being in the form of a slide 51 which, as hereinafter described more in detail, may be automatically shifted. 11 designates a music sheet carried by a roller 65 or spool 12 and adapted to be unwound therefrom and moved over the tracker bar. It is understood, of course, that the music sheet will have the usual note playing perforations, such as designated by the numerals 70 13, and the tracker bar will have openings 14 associated with the note playing mechanisms and controlled by the perforations in the music sheet.

In accordance with the present invention, 75 the middle section 10^a of the tracker bar, so far as variations in the length of the bar are concerned, is fixed against movement, and the sections on opposite sides of this fixed section are moved simultaneously towards the 80 fixed section in the event that the music sheet should contract in width, and are moved simultaneously away from the middle section in the event that the sheet should expand crosswise. To this end, there is provided a lever 15 pivoted, as at 16, and those sections of the tracker bar to one side of the middle section 10^a are connected by links 17 to the lever 15 at one side of its pivotal point, and the sections to the other side of the middle section 10^a are connected by links 18 to the lever 15 at the opposite side of its pivotal point. Thus, when the lever 15 is turned, the sections of the tracker bar to the left hand side of the fixed section will move in 85 one direction, and the sections on the right hand side will move in the opposite direction. It will be noted that the links for the two end sections are connected to the lever 15 at points further from the pivot of the lever than are the links connected to the second and fourth sections, the object of this arrangement being to cause the outer sections to move twice as far as the other two movable sections and thus take care of the accumulated expansion and contraction of the music sheet from the center to the edges thereof. In actual practice, the tracker bar may be made of more than five sections. By 90 way of illustration, the lever 15 is shown as being connected by a rod 20 to a pair of oppositely acting pneumatics 21 and 22, re-

spectively connected by tubes 23 and 24 to ports 25 and 26 located side by side in one of the end sections of the tracker bar. These tubes communicate by means of small bleed 5 openings 28 with an exhaust chamber 29 whereby the pneumatics will be exhausted when the ports 25 and 26 are closed. The note sheet is provided with a continuous line of spaced perforations or holes 30 which, 10 when the note sheet is properly tracking and the tracker bar is of proper extension, pass over the tracker bar between the ports 25 and 26 without uncovering either of these ports to any great extent. Preferably, but 15 not necessarily, the holes normally will lap over the ports, so as to make the control more sensitive. In the embodiment of Fig. 2, the bellows 21 and 22, and associated parts, are carried on the slideable support 51. 20 In order that the note sheet will properly track over the tracker bar, either the note sheet or the tracker bar, as a whole, is automatically shifted, the shifting movement being controlled by the note sheet. In the 25 embodiment shown in Fig. 1 the note sheet is shifted, and in Fig. 2 the tracker bar assembly is shifted. 30 Referring to the arrangement shown in Fig. 1, the bearings 35 for the spool or roller 12 are mounted for axial movement, and these bearings are normally urged lengthwise towards the right, as by means of a spring 37. 38 designates a lever adapted to cooperate with the right hand bearing. This 35 lever is connected by a rod 39 to a pair of oppositely acting pneumatics 40 and 41, respectively. These pneumatics are respectively connected by tubes 42 and 43 to ports 44 and 45 positioned side by side, preferably 40 in the fixed middle section of the tracker bar. The pneumatics 40 and 41 are adapted to be exhausted in the same manner as the pneumatics 21 and 22. The music sheet is provided preferably but not necessarily along 45 its center or medial line, with a continuous line of holes 46 arranged, when the sheet is in proper tracking position, to pass between the ports 44 and 45 without uncovering either of them to any great extent. 50 In the embodiment shown in Fig. 2, it may be assumed that the spool 12 is fixed against endwise movement. In this instance, the lever or link 38 is shown as being connected to the tracker bar support 51. 55 The operation of the arrangement shown in Fig. 1 is, briefly, as follows. In the event the music sheet is not properly tracking, the line of holes 46 will uncover to a greater extent either the port 44 or the port 45, depending on the direction in which the sheet 60 is misplaced, and, through the pneumatics 40 and 41, the sheet will be moved to proper tracking position. More specifically, assuming that the sheet has incorrectly shifted to 65 the left, the port 45 will be opened to the atmosphere by the holes 46 with the result that the pneumatic 41 will expand, withdrawing the lever 38 from the bearing 35 and permitting the spring 37 to move the bearings and roller slightly to the right. In 70 the event that the music sheet should shift out of registry slightly to the right, the holes 46 would uncover the port 44, whereupon the pneumatic 40 would move the lever 38 in a direction to cause the roller to be 75 properly shifted towards the left. In the event the music sheet should change in width, one or the other of the ports 25 and 26 (depending on whether the paper increased in width or decreased in width) will 80 be uncovered to a greater extent by the holes 30, with the result that the length of the tracker bar will be automatically changed, thereby bringing the sections to positions where the openings 14 properly register with 85 the note playing perforations of the sheet. More specifically, assuming that the music sheet should increase in width, the line of holes 30 would uncover the port 26 with the result that atmospheric pressure would be 90 admitted to the pneumatic 22, whereupon this pneumatic would return the lever 25 clockwise, thereby moving the sections slightly apart. In the event that the sheet would become narrower, the line of holes 30 would uncover the port 25, permitting air to flow to the pneumatic 21, with the result that the lever 15 would be oscillated 95 counterclockwise and the movable sections would be moved towards the fixed one. 100 The structure shown in Fig. 2 operates in a manner generally similar to that just described, except that instead of shifting the note sheet assembly including the sheet and its spool, the tracker bar as a whole or a single unit is shifted. In the event the note sheet should run out of line to the right, the port 44 would be opened whereupon the bellows 40 would shift the support 51, together with the tracker bar and the mechanism for changing the length of the bar, to 105 the right. Likewise, if the note sheet should run out of line to the left so that the port 45 would be uncovered, the tracker bar assembly would be moved to the left. 110 115 It will be noted that, by combining the means for varying the length of the tracker bar and the means for shifting the music sheet, each of these means being controlled by the music sheet cooperating with ports 120 in the tracker bar, the note playing perforations are caused to properly register with their respective note playing openings in the tracker sections. 125 As many changes could be made in the above construction and many apparently widely different embodiments of this invention could be made without departing from the scope thereof, it is intended that all matter contained in the above description or 130

shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, 10 might be said to fall therebetween.

What I claim is:—

1. In an automatic musical instrument, a tracker bar comprising a plurality of sections movable towards and away from each 15 other and an end section of said bar having a pair of ports positioned side by side, pneumatic means for changing the length of said bar and controlled through said ports, and a note sheet having along one edge a row of 20 holes normally tracking between said ports and adapted to control said ports and said pneumatic means therethrough.

2. In an automatic musical instrument, a tracker bar element, a music sheet element 25 including a music sheet adapted to pass over said bar element, and pneumatic means for shifting one of said elements relative to the other, said bar element having a pair of ports positioned side by side and connected 30 to said pneumatic means whereby when one of said ports is uncovered the pneumatic means will relatively move the elements in one direction and when the other of said ports is uncovered said pneumatic means 35 will relatively move said elements in the opposite direction, said sheet having a row of holes adapted to control said ports and normally tracking over the bar element between said ports.

3. In an automatic musical instrument, a tracker bar element including a tracker bar formed in sections, mechanism for moving said sections to vary the length of said bar, a music sheet element including a music 45 sheet adapted to pass over said bar, mechanism for shifting one of said elements to cause said sheet to properly track, ports in one of the end sections of said bar associated with said first mentioned mechanism, ports 50 in one of the sections between the end sections of said bar and associated with the second mentioned mechanism, said sheet having a row of holes controlling the first mentioned ports, said sheet having another set 55 of holes placed nearer the center of the sheet than the first row and controlling said second mentioned ports.

4. In an automatic musical instrument, a tracker bar element including a tracker bar formed in sections, mechanism for moving said sections to vary the length of the bar, a music sheet element including a music sheet adapted to pass over said bar, and mecha-

nism for shifting one of said elements to cause said sheet to properly track, said sheet 65 having, adjacent one edge, a continuous line of holes controlling said first mentioned mechanism and said sheet having along its medial longitudinal line a row of holes controlling said shifting mechanism. 70

5. In an automatic musical instrument, and in combination, a tracker bar formed in sections, mechanism for moving said sections to vary the length of said bar, a music sheet roll, a music sheet carried thereby, and mechanism for shifting said roll to cause said music sheet to properly track over said bar, said music sheet having a line of holes controlling said tracker bar mechanism, said sheet also having another line of holes controlling said shifting mechanism. 75

6. In an automatic musical instrument, and in combination, a tracker bar formed in sections, mechanism for moving said sections to vary the length of said bar, a music sheet 80 roll, a music sheet carried thereby, and mechanism for shifting said roll to cause the music sheet to properly track over said bar, said sheet having adjacent one edge a continuous line of holes controlling said 85 tracker bar mechanism, said sheet having on its medial line a row of holes controlling said shifting mechanism.

7. In an automatic musical instrument, and in combination, a tracker bar formed in 95 a plurality of sections, the central one of which is fixed, a music sheet, mechanism for moving said sections except the fixed one to vary the length of the tracker bar in accordance with variations in the width of said 100 music sheet, and means for shifting said music sheet, said music sheet having a line of holes adjacent one edge controlling said tracker bar mechanism, said sheet also having on its medial line a row of holes controlling 105 said shifting mechanism.

8. In combination, a tracker bar element including a tracker bar having sections movable towards and away from a central section, a music sheet element including a music sheet, means for moving said movable sections to vary the length of said tracker bar in accordance with the variations in the width of said music sheet, one of the end sections having a pair of ports positioned 110 side by side and associated with said mechanism, means for shifting one of said elements, the central section of said tracker bar having a pair of ports positioned side by side and associated with said shifting means, 115 said music sheet having a line of holes adjacent one edge normally passing between said first mentioned ports, said sheet also having a second row of holes normally passing between said ports in said central section. 120

JOHN T. AUSTIN.
